UNITED STATES PATENT OFFICE.

JOHN E. CHALMAN, OF CHICAGO, ILLINOIS, ASSIGNOR TO UNION SPECIAL MACHINE COMPANY, OF CHICAGO, ILLINOIS, A CORPORATION OF ILLINOIS.

ECCENTRIC CONNECTION.

Application filed April 23, 1921. Serial No. 464,043.

To all whom it may concern:

Be it known that I, JOHN E. CHALMAN, a citizen of the United States, residing at Chicago, in the county of Cook, State of Illinois, have invented certain new and useful Improvements in Eccentric Connections, of which the following is a description, reference being had to the accompanying drawing and to the figures of reference marked 10 thereon.

This invention relates to eccentric connections generally, and more particularly to means for oiling the eccentric which drives the needle lever of a sewing machine.

At the present time, the bearing surface between the eccentric and its strap is oiled by means of a wick or wiper sponge arranged in a bore in the top of the strap and the oil is generally fed to the sponge through 15 a bore in the needle lever, which bore registers with the bore in the strap. As a rule, the strap is also provided with an additional bore at the side for the reception of a second wiper sponge bearing on the wearing surfaces. The disadvantage of these prior constructions lies in the fact that when the eccentric is first oiled, on starting, it takes 20 considerable time for the oil to absorb through the wiper sponge and reach the eccentric surface. Furthermore, if the machine is left standing for any time, the supply of oil in the sponge dries up or the oil works back through the sponge and away from the bearing surface. So also the additional bore in the side of the strap weakens 25 the strap and unbalances it.

The main object of the present invention is to provide a device which will not only oil the eccentric surface immediately on 30 starting but will also maintain a supply of oil for the bearing at all times.

Another object of this invention is to eliminate the drying up of the oil in the bearing by providing a reservoir or pool of 35 oil located at the lowermost bearing surface of the eccentric so that the excess oil on the bearing will flow downwardly into the reservoir and assist in maintaining the pool for splashing the bearing.

Another object of this invention is to provide the eccentric strap with an internal reservoir communicating with the eccentric face at a point immediately beneath the eccentric and communicating with an inlet 40 or inlets on the exterior face of the strap,

which inlets are located substantially above the lowermost plane of the reservoir so that when oil is introduced into the reservoir through these inlets, it will blow to a point immediately beneath the eccentric to form 60 at this point, a gravity-fed pool of oil for splashing the bearing.

These and other objects will in part be obvious and will in part be hereinafter more 65 fully disclosed.

Referring more particularly to the accompanying drawings:

Figure 1 is a side elevation of the oiling device showing one of the oil inlets on the 70 exterior face of the strap;

Fig. 2 is a sectional view thereof on the line 2—2 of Fig. 1;

Figs. 3 and 4 are detail views of the strap sections, and

Fig. 5 is an enlarged sectional view of the 75 lower oiling strap showing the oil valve in section.

In general, the device includes the usual eccentric mounted on the main driving shaft of the machine surrounded by a two-piece eccentric strap for driving the needle lever. The lower section of the strap is bored, the bore inclining inwardly and downwardly from opposite points on the exterior face of the strap, to a point located immediately under the central portion of the eccentric. At this point, the upper wall of this strap is apertured so that the intermediate portion of the bore communicates with the eccentric surface. Each end of the bore communicating with the exterior of the strap is provided with a valve for the introduction of the oil and for retaining the oil in the bore. 80

Referring more particularly to the accompanying drawings, the base of the machine 1 is provided with the usual main drive shaft 2 upon which is mounted the pulley 3 and adjacent eccentric 4 surrounded by the eccentric strap comprising the upper strap section 5 and the lower strap section 6, the upper strap section being bored as at 7 at the top to receive the threaded end 8 of the needle lever connection rod 9 held in place by means of the nut 10. The wiper sponge or wick 11 is mounted in the bore 7 of the strap so as to bear on the periphery of the eccentric. 85

As in prior constructions, the upper and lower strap sections are held in assembled 90 position by means of screws 12 and 13 100

threading into bores in lateral flanges 14 and 15 on the sections.

My improved means for oiling the eccentric resides in forming the lower strap section with an oil reservoir located immediately beneath the eccentric. In the form illustrated, this reservoir is formed by providing the strap section 6 with two bores or recesses 16 and 17 which extend inwardly and downwardly from two points 18 and 19 on the opposite faces of the strap, meeting at a point 20 directly under the center of the driving shaft. This reservoir is arranged with its longitudinal axis extending in a plane at right angles to the longitudinal axis of the driving shaft. These opposite ends of the bores or recesses which are located at points 18 and 19, and which are located at points substantially above the bottom of the reservoir, constitute oil inlets for the introduction of oil into the reservoir. Preferably they are closed by spring seated retaining valves 21 and 22.

A simple form of valve comprises a shell-like cylinder 23 provided with an aperture in its outer end, which aperture is closed by a semi-spherical valve 24 having oppositely disposed fingers 25 for retaining a spring 26 in place between the valve 24 and the end of the shell-like cylinder 23. It is evident that any type of oil retaining valve may be used. It is furthermore evident that while one valve will suffice for this purpose, by the arrangement of the two valves on the opposite faces of the strap, oil may be introduced from one or the other side of the strap, depending upon the type of machine used. In order to provide a communication between the reservoir and the bearing surface of the eccentric, the upper wall of the lower strap section 6 is apertured as at 27 by which arrangement oil in the reservoir can easily splash upon or reach the

bearing surface of the eccentric from which point it will be carried around to the wiper 45 sponge 11, which wipes clean the bearing surface, retaining and absorbing some of the oil in the sponge. This sponge not only keeps the surface clean, but also prevents the grit from going back into the oil reservoir. 50

It is obvious that by inclining the bores 16 and 17 downwardly, the oil when initially inserted through either or both valves, will gravitate to the center of the reservoir, or in other words, to a point directly under the lowest portion of the eccentric. When the machine is at rest, the oil which has been previously picked up by the eccentric will also gravitate into the central portion of 60 the reservoir.

It is obvious that minor changes in the details of construction and in the arrangement of parts may be made without departing from the spirit of the invention as set forth in the appended claim. 65

Having thus described the invention, what I claim as new and desire to secure by Letters Patent, is—

In a device of the class described, the combination with a driving shaft provided with an eccentric; of a strap surrounding said eccentric, said strap being formed with an internal recess in its lowermost portion immediately beneath said eccentric and communicating with said eccentric, said recess extending from said central portion of the strap immediately beneath said eccentric upwardly and outwardly on each side thereof to the opposite exterior faces of said strap, and oil retaining valves respectively, arranged in the opposite ends of said bore. 75 80

In testimony whereof, I affix my signature.

JOHN E. CHALMAN.
